Patented Sept. 2, 1975

236,581

STRAP LOCK FOR LUGGAGE

Sam Reisner, 550 Hanley Ave.,
Los Angeles, Calif. 90049

Filed Oct. 19, 1973, Ser. No. 408,187

Term of patent 14 years

Int. Cl. D8—07

U.S. Cl. D8—122

FIG.2

FIG.1

FIG.3

FIG.4

FIG.5

FIG. 1 is a side perspective view of a strap lock for luggage showing my new design in a position of use;

FIG. 2 is an enlarged front elevational view thereof;

FIG. 3 is a top plan view thereof with the strap end in a slightly altered position;

FIG. 4 is a rear elevational view thereof; and

FIG. 5 is an enlarged fragmentary bottom plan view of the strap lock for luggage showing the lock portion and part of the belt.

I claim:

The ornamental design for a strap lock for luggage, substantially as shown and described.
